UNITED STATES PATENT OFFICE

2,462,240

TWO-TEMPERATURE REFRIGERATOR
SYSTEM

Paul D. Van Vliet and Bartell J. Homkes, Galesburg, Ill., assignors to Liquid Carbonic Corporation, Chicago, Ill., a corporation of Delaware

Application March 21, 1945, Serial No. 583,925

11 Claims. (Cl. 62-4)

1

This invention relates to an improvement in refrigerators and is adapted for use in domestic refrigerators.

One purpose is to provide an improved two temperature refrigerator.

Another purpose is to provide a two temperature refrigerator in which a single refrigerant condensing unit is employed to circulate a volatile refrigerant through evaporators employed to cool separate storage compartments to different temperatures.

Another purpose is to provide improved control means for a two temperature refrigerator.

Another purpose is to provide an improved refrigerant circuit for two temperature refrigerators.

Another purpose is to provide an improved system for delivering liquid refrigerant selectively to the evaporators of separate compartments in a two temperature refrigerator.

Other purposes will appear from time to time in the course of the specification and claims.

The invention is illustrated more or less diagrammatically in the accompanying drawings wherein:

Figure 1 is a vertical section of a two temperature refrigerator;

Figure 2 is a section at the line 2-2 of Figure 1;

Figure 3 is a diagrammatic showing of the refrigeration system and electrical circuit; and

Figure 4 is a diagrammatic showing of an alternative defrosting means.

Like parts are indicated by like symbols throughout the specification and drawings.

Referring to the drawings, A generally indicates a food storage cabinet including an insulated back wall 1, insulated side walls 2, an insulated top wall 3, an insulated bottom wall 4, and an insulated intermediate partition 5. The above mentioned walls and partitions define two storage compartments which are separated from and insulated from each other. 6 is an insulated door for the upper compartment and 7 an insulated door for the lower compartment. Thus the two storage compartments are insulated from each other and from the outside air. Any suitable gasketing or sealing means may be employed, it being understood that the details of the walls, doors and sealing means do not of themselves form part of the present invention. Any suitable means may be employed for limiting to a minimum heat transfer between the inside of the compartments and the outside air, and between the two compartments.

2

For convenience, the upper compartment is indicated as B and the lower compartment as C. Located below the lower compartment C is an uninsulated space for a condensing unit, with a closure 16.

The upper storage compartment B is preferably held at a relatively high temperature as from 35 to 45 degrees Fahrenheit. The interior of the compartment C may be maintained at a temperature substantially below freezing, as from 0 to 10 degrees Fahrenheit, to adapt it for quick freezing and for cold storage of frozen goods.

Referring to the details of the compartments, it is advantageous to employ a liner or sleeve of sheet metal for each compartment, with evaporator coils on the exterior of each such sleeve, in heat transfer relationship therewith. In connection with the upper compartment B is indicated a sleeve including a vertical rear wall 11, side walls 12, a top wall 13, and a bottom wall 14. 15 indicates an evaporator coil which may extend about three sides of the liner or sleeve thus formed, namely about the rear wall 11 and each of the side walls 12. The length of the coil and the area of wall with which it is in contact may be varied to cause the refrigerant to be evaporated at the desired temperature, preferably somewhat above freezing, to prevent frost and to minimize dew formation on the walls, and to insure a sufficiently high relative humidity to prevent dehumidification of stored food. The storage space of compartment B is bounded at the bottom by an insulating food storage shelf 16 which is shown as supported several inches above the bottom wall 14, of the upper sleeve. It is convenient to identify the space below the insulating food shelf as the ice cube forming and storage compartment E. In the compartment E is illustrated a shelf including an evaporator coil 17, this coil or evaporator being in series with the evaporator 15. It is effective to freeze the contents of any suitable ice cube tray or trays 18. Interposed in the line from evaporator 15 to evaporator 17 is a restrictor diagrammatically illustrated at 71. Positioned 45 below the evaporator 17 is any suitable defrosting pan 19. Any suitable gap or gaps 20 may be employed between the insulating shelf 16 and the side walls and door of the compartment B. This air gap provides a connecting vapor path or paths between compartment E and the compartment B, to permit excess water vapor to be withdrawn from the air in compartment B. The storage shelf 16 may preferably be permanently 50 fixed in relation to the upper sleeve, with suitable 55

gaps or apertures provided, or it may be removably mounted on any suitable supports such as the spacing and supporting pins 21.

In compartment C is a liner sleeve including the back wall 25, side walls 26, bottom wall 27 and top wall 28. As in the case of the upper sleeve, any suitable evaporator coil 29 may extend about the sleeve, being preferably exterior thereto but in heat transfer relationship therewith. The length and shape of the coil may be varied to suit desired conditions but it may advantageously extend about the walls 25, 26 and 28, being preferably omitted from the bottom wall 27.

With reference to the refrigerant condensing unit employed, any suitable means may be used. The particular mechanism herein illustrated is of the mechanical type. Since its details are not of themselves important the mechanism is illustrated only diagrammatically. 30 illustrates any suitable compressor, driven for example from the motor 31. 32 is any suitable condenser coil and 33 a receiver. Any suitable means may be used to cause air to flow through the condenser, such as a fan on motor 34, or a separate motor and fan, or a chimney. The liquid refrigerant, under pressure, is delivered along the duct 34 to the thermal expansion valve generally indicated as 35, which may be of the type which has no thermal bulb and capillary tube but instead, has the suction gas returning through line 36, pass through the valve body, and apply suction pressure to the usual thermal expansion valve diaphragm, thus controlling superheat. 37 is a duct extending from the valve structure 35 to the three way solenoid valve 38, the details of which do not form part of the present invention and are not illustrated. It will be understood, however, that a liquid line 39 extends to the lower compartment C and a liquid line 40 to the upper compartment B. Any suitable means may be employed, such as the restrictor tubes 41 and 42, for maintaining pressure on the solenoid valve ports to prevent liquid refrigerant from expanding within the solenoid valve. When the refrigerant is circulating through the evaporator 15 it returns by the pipe 43 to the suction line 36. In series with the evaporator 15 is the ice cube tray shelf evaporator 17. 45 diagrammatically indicates a manual valve which permits shutting off the flow of refrigerant through coil 17, to permit defrosting. A bypass relief valve 44 normally shut, but opening when valve 45 is closed is provided, thus maintaining refrigeration on evaporator 15 whether valve 45 is open or closed. Another means of defrosting is diagrammatically shown in Figure 4 utilizing a three way manual valve 72 in the line 43 from the evaporator 15 in one position feeding refrigerant through the restrictor 71 to the ice freezing evaporator 17, and in another position feeding direct to the suction line 36. In the second position there is no refrigerant flow through the evaporator 17 and defrosting will occur.

It will be understood that when refrigerant is flowing through the evaporator 15, no refrigerant is flowing through the evaporator of the lower or colder compartment C. When the solenoid valve 38 is set to deliver refrigerant through tube 39 and restrictor 41 to the low temperature evaporator 29, the refrigerant returns to the suction tube 36 through the tube 43. 48 is any suitable check valve in the pipe 43, adapted to prevent gas in the suction line from entering and

condensing in evaporator 29 when that evaporator is not being supplied with refrigerant.

The electrical circuits are as follows:

Current supply is through leads 50 and 51. Lead 51 runs to contact 67 in the switch 65 and the contacts 58 and 68 in the switch 53. When either switch is closed, current flows to the contact 66 in the switch 65 or the contact 54 in the switch 53, thence through the lead 52 to the motor 31 and to the return lead 58, causing the motor to run when either or both switches are closed.

When the switch 53 closes, the second contacts also close, current flowing to the contact 55 through the lead 56 to the solenoid of the valve 38, returning through the lead 57 to the return lead 58. Thus the solenoid-operated three way valve 38 is made to deliver refrigerant to the evaporator 15 when the switch 53 is closed, and to the evaporator 29 when the switch 53 is open.

Both switches are operated thermally, with heat sensitive bulbs located in their respective compartments. In the operation of the device, with compartments B and C both warm, and calling for refrigeration, the switches 53 and 65 will both be closed. The solenoid of the valve 38 will be energized and it will deliver refrigerant along the pipe 40, through the restrictor 42, to the evaporator 15 of the upper or warmer compartment B. When the compartment B is cooled to the desired temperature, the double pole switch 53 opens. The result is to alter the direction of flow from the solenoid valve and to cause refrigerant to flow through the tube 39 and restrictor 41 to the evaporator 29 in the low

temperature compartment C. The motor 31 continues to run because switch 65 is still closed. Operation continues until the lower compartment C is at the desired temperature, or until the upper compartment B again calls for refrigeration and closes the switch 53. Thus it will be clear that the upper compartment B is always refrigerated when the switch 53 is closed. That is to say, the bulb 62 in the upper compartment, through the bellows 61, or some equivalent heat responsive means, can always control the three way solenoid valve 38 to insure that, whenever refrigeration is called for by a rise in temperature in the compartment B, the refrigerant is thereupon delivered to the evaporator 15 of the upper compartment for evaporation. But should the flow of refrigerant to the lower evaporator 29 be interrupted by demand for refrigeration for the upper compartment B, it will be resumed at once when the temperature in the upper compartment is sufficiently lowered to open the switch 53. When neither compartment calls for refrigeration, the switches 53 and 65 are both open, in response to action of the bulbs 62 and 68, and the circuit through the motor 31 is broken, and no refrigerant is delivered.

The advantages of the above described arrangement are many. The single refrigerating mechanism, with a single compressor and condenser, always operates at maximum suction pressure for either the high temperature or the lower temperature evaporator, whichever is in circuit, and operates at maximum output. The critical food compartment temperature is closely controlled. The evaporator coils can be of smaller tubing, because they operate independently, and not in series. A single refrigeration condensing unit delivers refrigerant selectively to one or the other evaporator, but never to both at the same time.

65

68

70

75

In effect the two refrigerant condensing units shown in the co-pending application Ser. No. 583,924 are replaced by the solenoid valve 38, the expansion valve 35 and receiver 33, and a single pump or compressor having a somewhat greater capacity than that of either of the two compressors of the dual pump system.

The manual shut off valve 45 in the evaporator tray coil 17 is placed at the front for easy access. The relief valve 44 serves as a bypass to let refrigerant gas from the evaporator 15 pass directly to the suction pipe 36 when the manual shut off valve 45 is closed. The valve 44 may have a spring so adjusted that it is tightly shut when the valve 45 is open.

To defrost, the valve 45 is closed and is reopened when the evaporator 17 is clear of ice. If forgotten, the only effect is that water will not be frozen by the evaporator 17. Refrigeration to the food compartment continues, even though the valve 45 is carelessly left shut.

Whereas the evaporator 17 is shown in series through the restrictor 11 with the evaporator 15 of the warm compartment B it may, if desired, be included instead in the low temperature circuit, in series with the evaporator 29 and without the restrictor 11. Defrosting procedure is the same, and refrigeration to compartment C continues even though the valve 45 is carelessly left shut.

It will be realized that, whereas, a practical and operative device is described and illustrated, nevertheless many changes may be made in the size, shape, number and disposition of parts without departing from the spirit of the invention. Therefore the description and drawings are to be taken as illustrative or diagrammatic, rather than as limited to the precise showing.

The use and operation of the invention are as follows:

The requirements of a refrigerator having two compartments, one held at say 40 degrees F and the other at say from 0 to 19 degrees F. are that control of temperature in the warm compartment must be close, whereas a wider temperature fluctuation of the colder compartment is permissible. It is of primary importance to keep the refrigeration demand of the upper compartment B satisfied. In the present system each compartment is provided with heat responsive means for causing a flow of refrigerant to its evaporator, when the temperature in the compartment reaches a predetermined maximum. The present system is intended to insure that the call for refrigeration of the warmer compartment B takes precedence over the call for refrigeration of the colder compartment C.

We claim:

1. In a household refrigerator, a condensing unit, an evaporator in fluid circuit therewith, a storage compartment in which said evaporator is positioned, a second evaporator, in series with said first mentioned evaporator, adapted for ice cube freezing, a restricted passage between said evaporators, a shut off valve for said second evaporator adapted, when closed, to prevent the flow of refrigerant through said second evaporator, and bypass means adapted to permit a return flow of refrigerant from said first mentioned evaporator to said condensing unit when said shut off valve is closed.

2. In a household refrigerator, a storage compartment, a condensing unit, a space cooling evaporator in said storage compartment, in fluid circuit with said condensing unit, constructed and arranged to maintain an above freezing temper-

ature in said storage compartment, a second evaporator in said compartment, constructed and arranged to maintain a temperature sufficiently low for ice cube freezing, a shut off valve for said second evaporator, adapted, when closed, to prevent the flow of refrigerant through said second evaporator, and to cause its defrosting, and means for maintaining said space cooling evaporator in fluid circuit relationship with said condensing unit during the closure of said shut off valve.

3. In a household refrigerator, an insulated compartment, an expansion coil adapted to cool said compartment, means for circulating a volatile refrigerant through said coil, including a condensing unit in circuit therewith, a restrictor adapted to reduce the pressure of the refrigerant from said coil, a second expansion coil in series with the first coil and with the condensing unit, adapted for the freezing of cubes of ice, a shut off valve for said second expansion coil, adapted to prevent flow of refrigerant through said coil, and a normally closed bypass relief valve adapted to permit refrigerant to flow from the first coil back to the condensing unit when said shut off valve is closed.

4. In a household refrigerator, an insulated compartment, an expansion coil adapted to cool said compartment, means for circulating a volatile refrigerant through said coil, including a condensing unit in circuit therewith, a restrictor adapted to reduce the pressure of the refrigerant supplied to said coil, a second expansion coil, in series with the first coil and with the condensing unit, adapted for the freezing of cubes of ice, a restrictor for said second coil, a shut off valve for said second expansion coil, adapted to prevent flow of refrigerant through said coil, and a normally closed bypass relief valve adapted to permit refrigerant to flow from the first coil back to the condensing unit when said shut off valve is closed.

5. In a household refrigerator, an insulated compartment, an expansion coil adapted to cool said compartment, means for circulating a volatile refrigerant through said coil, including a condensing unit in circuit therewith, a restrictor adapted to reduce the pressure of the refrigerant supplied to said coil, a second expansion coil, in series with the first coil and with the condensing unit, adapted for the freezing of cubes of ice, a restrictor between said coils, adapted to reduce the pressure supplied to said second coil, and means for causing defrosting said second coil comprising a three way manual valve and connections therefor, adapted when in one position to deliver refrigerant from the first coil through said last mentioned restrictor and said second coil and thence back to the condensing unit, and adapted when in another position to deliver refrigerant from the first coil directly back to the condensing unit.

6. In a household refrigerator, an insulated compartment, a space cooling evaporator positioned in said compartment and constructed and arranged to maintain a temperature of above freezing in said compartment, a second evaporator in said compartment, adapted to freeze ice, a restricted refrigerant connecting tube between said two evaporators, a refrigerant condensing unit and connections therefor, adapted to deliver liquid refrigerant to the space cooling evaporator and to withdraw gaseous refrigerant from the freezing evaporator, and means effective during normal circulation of refrigerant through said space cooling evaporator,

for bypassing the refrigerant about said freezing evaporator.

7. In a refrigerator system, a pair of insulated compartments adapted to be cooled to different temperatures, a separate evaporator for each compartment, constructed and arranged to cool said compartments to their desired temperatures, a single condensing unit in circuit with said evaporators, a motor therefor, an expansion valve in said circuit, a three way solenoid valve in said circuit, beyond said expansion valve, adapted to deliver refrigerant selectively to one or the other of said evaporators, in response to the energization or de-energization of said solenoid valve, a thermal switch responsive to temperature in the warmer compartment, said switch having two sets of contacts, one set adapted and connected to energize the solenoid valve and the other adapted and connected to energize said motor, and a second thermal switch, responsive to the temperature of the colder compartment, said switch including a single set of contacts adapted and connected, when closed, to energize said motor.

8. In a refrigerator system, a pair of insulated compartments adapted to be cooled to different temperatures, a separate evaporator for each compartment, constructed and arranged to cool said compartments to their desired temperatures, a single condensing unit in circuit with said evaporators, a motor therefor, a three way solenoid valve in said circuit, adapted to deliver refrigerant selectively to one or the other of said evaporators, in response to the energization or de-energization of said solenoid valve, a thermal switch responsive to temperature in the warmer compartment, said switch having two sets of contacts, one set adapted and connected to energize the solenoid valve and the other adapted and connected to energize said motor, and a second thermal switch, responsive to the temperature of the colder compartment, said switch including a single set of contacts adapted and connected, when closed, to energize said motor.

9. In a refrigerator system, a pair of insulated compartments adapted to be cooled to different temperatures, an evaporator for each said compartment, a condensing unit in circuit with said evaporators and motor therefor, a three way solenoid valve in said circuit, said circuit including fluid lines extending from said three way valve to the evaporator of each said compartment, restrictors in each said line, switch

means adapted to control said solenoid valve in response to temperature conditions in the warmer of said compartments, whereby refrigerant is fed to the evaporator of the warmer compartment whenever the temperature of said compartment rises above a predetermined minimum, and means effective to cause refrigerant to be fed to the evaporator of the colder compartment, whenever the temperature of said colder compartment exceeds a predetermined minimum at a time that refrigerant is not being fed to the warmer compartment.

10. In a refrigerator system, two expansion coils, an expansion valve, a three way solenoid valve, and means for feeding a refrigerant from said expansion valve through said three way valve selectively to said expansion coils, including switching means adapted to energize or de-energize the solenoid valve, and restrictor tube means adapted to maintain such a pressure on the delivery parts of the three way valve as to maintain solid liquid through said valve.

11. In a household refrigerator, a refrigerant condensing unit, a storage compartment, a space cooling evaporator, in fluid circuit with said condensing unit, arranged to maintain an above freezing temperature in said storage compartment, a second evaporator in said storage compartment, constructed and arranged to maintain a temperature sufficiently low for ice cube freezing, and means including a valve element selectively movable to one position to permit the flow of refrigerant through the second evaporator or to a second position to cause defrosting of the second evaporator by completely stopping the flow of liquid and gaseous refrigerant therethrough.
